(57) **CLAIM**

The ornamental design for a mechanic's creeper, as shown and described.

DESCRIPTION

FIG. 1 is a top, front, side, left end perspective view of a mechanic's creeper showing my new design;

FIG. 2 is a top plan view thereof;

FIG. 3 is a front side elevational view thereof, the rear side elevational view being identical;

FIG. 4 is a left end elevational view thereof, the right end elevational view being identical;

FIG. 5 is a cross-sectional view, taken substantially along the line 5—5 of FIG. 2; and,

FIG. 6 is a bottom plan view thereof.
